UNITED STATES PATENT OFFICE.

CHARLES S. BURTON, OF OAK PARK, ILLINOIS.

VACUUM FUEL-FEED DEVICE FOR INTERNAL-COMBUSTION ENGINES.

1,400,723.

Specification of Letters Patent. Patented Dec. 20, 1921.

Application filed June 16, 1920. Serial No. 389,285.

To all whom it may concern:

Be it known that I, CHARLES S. BURTON, a citizen of the United States, residing at Oak Park, in the county of Cook and the 5 State of Illinois, have invented certain new and useful Improvements in Vacuum Fuel-Feed Devices for Internal-Combustion Engines, of which the following is a specification, reference being had to the accompanying drawings, forming a part thereof.

The purpose of this invention is to provide an improved device for supplying liquid fuel from a low level main supply tank to a carburetor of an internal combustion 15 engine, particularly adapted for such service in connection with the engine of a motor vehicle. It consists in the elements and features of construction shown and described as indicated in the claims.

20 In the drawings:—

Figure 1 is a diagrammatic view showing a device embodying this invention in positional relation to the main supply tank and carburetor of a motor vehicle engine.

25 Fig. 2 is a vertical axial section of a chamber and connections containing the distinguishing features of this invention.

Fig. 3 is a view similar to Fig. 2 showing a slight modification of the construction:

30 In the drawings 1 represents the main low level fuel supply tank of a motor vehicle. 2 is a carburetor of the engine on such a vehicle. 3, 3, are pipe line connections from the tank, 1, to the carburetor, 2, said pipe line connections comprising a T-fitting, 4, a pipe member, 5, extending from the stem of the T upward to a chamber, 6, which is also included in the conduit from the main low tank to the carburetor. 7 is a pulsator 35 comprising a cylinder, and a piston, 8, reciprocated therein by any convenient means which may be operated by the engine, as by an eccentric, 9, mounted on a shaft, 10, rotated in any manner by connection with the 40 engine or its parts or accessories, not shown.

45 11 is a pipe communicating from the chamber of the pulsator to the top of the chamber, 6, for producing alternately condition of partial vacuum and pressure in said 50 chamber, 6, upon the alternate strokes in opposite directions of the piston, 8, of the pulsator. It will be understood that this action causes the entire construction to operate substantially as a pump, the suction 55 stroke of the pulsator producing partial vacuum in the chamber, 6, tending to lift the

fuel from a tank, 1, through pipe, 3, past the check valve, 12, in one branch of the T, and the compression stroke of the pulsator forcing the liquid out of the chamber, 6, 60 past the check valve, 13, out toward the carburetor.

In this operation it will be seen that the liquid fuel will continue to be lifted as long as the engine is in operation, regardless of 65 the requirements of the carburetor, and that eventually all the passages back to the pulsator will become filled with liquid, and that thereafter subsequent action of the pulsator operating without relief would tend to burst 70 the connections. It is necessary, therefore, to provide means for preventing the lifting of the liquid by the action of the pulsator, or preventing the liquid from being driven on by the pressure stroke after the chamber, 75 6, is filled to a certain height. For this purpose the chamber, 6, is provided with an atmosphere vent device and the means for controlling it which will now be described. The cap plate, 15, of the chamber, 6, has on 80 the upper side a hollow boss, 16, which is bored for connection at one end with the pipe, 11, leading from the pulsator, the bore opening freely at its lower side into the cavity of the chamber, 6, and constituting 85 substantially a part of that cavity. At the end of the bore opposite that at which the pipe, 11, is connected, there is formed a valve seat, 17, through which a port, 18, opens to the atmosphere. A dust screen, 19, 90 may be provided beyond the port,—that is, on the atmosphere side, to exclude dust. In the form shown in Fig. 3 this valve seat, 17, constitutes substantially a diaphragm or partition in the bore of the boss, 16, and the 95 face which constitutes the valve seat is substantially vertical,—that is, at right angles to the axis of the boss. A disk valve, 20, is provided, standing on edge, adapted to seat against this seat for closing the atmos- 100 phere port, and to lean slightly away from its seat for opening, check pins, 21, being provided to limit its movement away from its seat. A weighted latch, 22, pivoted for swinging in the vertical plane of the axis 105 of the atmosphere vent port, operates by gravity for holding the vent controlling valve seated. A float, 25, in the chamber, 6, is provided with a stem, 26, by which it is guided in a vertical path, the stem ex- 110 tending down through the pipe, 5, and obtaining guidance in a spider, 27, at the open-

ing in the chamber, 6, to which the pipe, 5, is connected, and by a cross pin, 28, in the lower end of said stem. The float, 25, has projecting from its upper side at the center 5 a finger, 29, which engages the latch, 22, for lifting it away from valve-locking position when the float has been lifted by the inflow of liquid into the chamber, 6, to a predetermined height, which is in fact determined in the construction of the device 10 by the dimensions of the parts, particularly the length of the finger, 29.

The operation of this construction, it will be seen, is that when the liquid has been 15 accumulated in the chamber, 6, to a point causing the float to lift the latch, 22, the vent-controlling valve, 20, will be free to open upon the suction stroke of the pulsator, and the atmosphere relief thus afforded prevents the production of partial vacuum in 20 the chamber, 6; but upon the pressure stroke of the pulsator the valve will be seated, and the pressure will operate to force the liquid from the chamber, 6, on toward the carbureter, 25 eventually lowering the level of the liquid and permitting the float to drop to release the latch, which will again fall into valve-closing and locking position; and thereupon the pressure stroke and the 30 vacuum stroke of the pulsator will operate for producing respectively pressure and partial vacuum in the chamber, 6, causing the pumping action to be resumed, until again the level of the liquid in the chamber becomes such as to cause the float to lift the 35 latch and release the vent valve.

In the form shown in Fig. 2, the seat for the atmosphere vent valve, 20, is slightly inclined so that the valve tends normally to be seated; and a shoulder, 16^a, in the bore of 40 the boss, 16, serves to retain the valve in the vicinity of the seat. The seat is most conveniently formed by means of a sleeve, 16^x, having its inner end cut aslant, to afford the 45 inclined seat described, the sleeve being driven in liquid and air tight into the end of the bore toward which the shoulder, 16^a, faces. A dust screen, 19^x, is inserted and secured outside the sleeve. Instead of a 50 weighted latch for seating the vent valve, 20, there is provided a latch, 22^x, fulcrumed for swinging at its free end nearly to a position at right angles to the inclined valve seat by the time it has reached the outer face 55 of the valve lying against said seat; and in that position the latch is subject to encounter of the upstanding finger, 29^x, of the float which lifts it to a stop pin, 29^y. At this 60 position the latch prevents the valve from escaping from the vicinity of its seat, or passing vertical position. It is therefore certain to be seated by the pressure impulse of the pulsator. It will be noticed that in

this form the angle at which the latch extends to hold the valve, 20, seated is so near 65 a right angle to the valve that though, being slightly less than a right angle, it is certain to hold the valve against its seat, and cannot be moved by any outward tendency of the valve, as upon the suction impulse. That is 70 to say, the lever extends at what may be called a positive locking angle to the valve and exposed to the action of the float, which upon rising to the predetermined height lifts the latch to the position shown in dotted line in Fig. 3, releasing the valve, 20, so that it is free to be drawn from its seat by the suction, but is checked by the latch against passing vertical position, and will therefore return to its seat by gravity upon 75 cessation of suction.

In this respect this form is to be distinguished from that shown in Figs. 2 and 4.

I claim:—

1. In a device for the purpose indicated, 85 a conduit for connecting a main low level liquid supply tank with the carbureter to be supplied therefrom; a chamber comprised in said conduit; check valves in the conduit respectively antecedent and subsequent to 90 the chamber, both opening for flow toward the carbureter; a pulsator communicating with the upper part of said chamber for alternately producing partial vacuum and pressure therein; an atmosphere vent means 95 communicating with said chamber; a valve which controls said vent positioned with respect to its seat for being normally opened by the suction impulse and held closed by the pressure impulse of the pulsator; movable 100 means for holding the valve closed against the suction pull tending to open it; a float in the chamber, and means operated by the rise of the float to a predetermined height for withdrawing said movable means 105 from valve-holding position.

2. In the construction defined in claim 1 foregoing, the vent-controlling valve being a disk upstanding on edge, and the valve seat being approximately in a vertical plane. 110

3. In the construction defined in claim 1 foregoing, the vent-controlling valve being a disk upstanding on edge, and the valve seat being slightly inclined away from vertical position of the valve, and means for 115 checking the valve against movement away from its seat past the vertical position.

4. In the construction defined in claim 1 foregoing, the movable means for holding the valve closed being a pivoted latch device 120 which is gravity-operated for locking the valve on its seat.

In testimony whereof, I hereunto set my hand at Chicago, Illinois, this 7th day of June, 1920.

CHARLES S. BURTON
